UNITED STATES PATENT OFFICE.

HOWARD W. BRACKEN, OF HOPEDALE, MASSACHUSETTS, ASSIGNOR TO DRAPER COMPANY, OF HOPEDALE, MASSACHUSETTS, A CORPORATION OF MAINE.

LOOM-SHUTTLE.

No. 851,647.

Specification of Letters Patent.

Patented April 30, 1907.

Application filed November 24, 1906. Serial No. 344,815.

To all whom it may concern:

Be it known that I, HOWARD W. BRACKEN, a citizen of the United States, and a resident of Hopedale, county of Worcester, State of Massachusetts, have invented an Improvement in Loom-Shuttles, of which the following description, in connection with the accompanying drawings, is a specification, like letters on the drawing representing like parts.

10 This invention relates to loom-shuttles used in looms of the automatic filling-replenishing type, such, for instance, as shown in United States Patent No. 529940, granted to Northrop November 27, 1894, wherein a 15 fresh filling-carrier or bobbin is automatically inserted in the running shuttle at the proper time.

The head of the filling-carrier is engaged and held in position by a holder provided 20 with spring-jaws, the annularly-ribbed head being inserted between them, and an inclined directing-plate or guide is located between the jaws, to direct the head into proper position to be engaged by the jaws.

25 It has been found that the impact of the head of an incoming filling-carrier upon the inclined guide tends to push the bent back upper end thereof toward the adjacent end of the shuttle, into the wood of the shuttle-body, so that the positioning of the head with 30 relation to the jaws is at times faulty.

In my present invention I have provided a simple and positive lock between the holder and the upper end of the guide, so that there 35 can be no longitudinal movement of the guide with relation to the holder, thereby overcoming the objection referred to.

The novel features of my invention will be 40 fully described in the subjoined specification and particularly pointed out in the following claims.

Figure 1 is a top plan view of the holding 45 end of a loom-shuttle of the type referred to, with one embodiment of my present invention applied thereto, the shuttle-body being partly broken out; Fig. 2 is a partial longitudinal section on the line 2—2, Fig. 1.

The shuttle-body A having a longitudinal opening A' therein open from top to bottom 50 of the body to receive the filling-carrier and permit the passage therethrough when ejected, is of usual construction in shuttles of the specified type. At one end of the opening

the body is recessed at 1 to receive the holder 2, made as a metal block having parallel sides, and flat, parallel top and bottom faces, the front end of the holder having two spring jaws 3, extended into the opening A'. Said jaws are preferably grooved, at 4, to receive the usual annular projections, ribs or 55 rings on the head of the filling-carrier, which is thereby engaged and securely held in position in the opening A'.

The inclined directing-plate or guide 5, which assists in directing the filling-carrier 65 into position, is located between the jaws and preferably is made of resilient metal, as usual, the lower end of the guide being bent back at 6 to extend beneath the holder 2, between it and the bottom of the recess 1, see Fig. 2. 70 The upper end of the guide is bent down at 7, and then rearwardly extended, at 8, upon the top of the holder, and in practice the side edges of the extension enter grooves, as 1^x, 75 see Fig. 1, formed in the side-walls of the recess 1.

The construction thus far described is not of my invention, and is well-known to those skilled in the art.

Heretofore the end of the extension 8 has 80 been bent down to form a lip 9, as herein, which fitted over a transverse shoulder on the top of the holder, and between it and the outer end of the recess 1. When so constructed, however, the impact of the head of 85 the incoming filling-carrier on the guide 5 tends to force rearward the extension 8 against and into the wood forming the end of the recess in the shuttle-body, so that the guide becomes loose and gives so much that 90 the filling-carrier is not properly positioned between the jaws 3. In accordance with my invention I obviate this objection by forming a transverse slot 10 in the top of the holder, into which slot the lip 9 enters, thereby forming 95 a positive lock between the holder and the guide, so that the latter cannot work loose or have any longitudinal play relative to the holder. Manifestly the end of the recess 1 has no function in resisting the thrust 100 of the extension 8, as it is taken up by the rear wall of the slot 10, and the single screw 11 passed through the holder into the walls of the shuttle-body retains the holder and guide in place.

Having fully described my invention, what

I claim as new and desire to secure by Letters Patent is:—

1. A loom-shuttle having an opening therein, a holder fixedly mounted in the shuttle-body at one end of the opening and provided with jaws to engage the head of a filling-carrier, an inclined guide between the jaws and having a rearward extension projecting above the holder, and a positive lock between the latter and the extension and independent of the shuttle-body to prevent movement of the guide backward or forward relatively to the holder.
2. A holder having a pair of spring-jaws to engage the end of a filling-carrier, said holder

having on its top a transverse slot, a coöperating guide inclined between the jaws and having its ends bent back to receive between them the holder, the upper one of said ends having a downturned lip to enter the slot in the holder and thereby positively lock the guide thereto.

In testimony whereof, I have signed my name to this specification, in the presence of two subscribing witnesses.

HOWARD W. BRACKEN.
